[57] **CLAIM**

The ornamental design for an automobile grill, as shown and
described.

DESCRIPTION

FIG. 1 is a front perspective view of an automobile grill
showing my new design;

FIG. 2 is a right side elevational view thereof, the left side
being a mirror image of that shown;

FIG. 3 is a front elevational view thereof;

FIG. 4 is a top plan view thereof;

FIG. 5 is a bottom plan view thereof;

FIG. 6 is a rear elevation view thereof;

FIG. 7 is a front perspective view of an automobile grill
showing a second embodiment of my new design; and,

FIG. 8 is a front elevational view thereof.

The side, top and bottom views are the same in appearance
as in FIGS. 2, 4 and 5 and the rear view is substantially
similar in appearance as in FIG. 6.
